UNITED STATES PATENT OFFICE

165,742

ELECTRIC RANGE

Edwin R. Culver, Jr., St. Louis, Mo., assignor to Wrought Iron Range Company, St. Louis, Mo., a corporation of Missouri

Application March 28, 1951, Serial No. 14,651

Term of patent 3½ years

(Cl. D81—4)

To all whom it may concern:

Be it known that I, Edwin R. Culver, Jr., a citizen of the United States and a resident of the city of St. Louis, State of Missouri, have invented a new, original, and ornamental Design for an Electric Range, of which the following is a specification, reference being had to the accompanying drawings, forming a part thereof.

Fig. 1 is a top plan view of an electric range embodying my new design;

Fig. 2 is a front elevational view thereof;

Fig. 3 is an elevational view from one end thereof;

Fig. 4 is an elevational view of the backguard panel from the opposite end of Fig. 3;

Fig. 5 is a greatly enlarged front elevational view of the backguard panel shown in full lines;

Fig. 6 is a sectional view taken at line 6—6 of Fig. 5;

Fig. 7 is a further sectional view taken at line 7—7 of Fig. 5; and

Fig. 8 is also a sectional view taken at line 8—8 of Fig. 5.

The characteristic features of my design for an electric range or those portions shown in full lines in the drawing.

I claim:

The ornamental design for an electric range, substantially as shown and described.

EDWIN R. CULVER, JR.
